UNITED STATES PATENT OFFICE

KARR PARKER, OF BUFFALO, NEW YORK

SOUND-REPRODUCING SET

Application filed September 18, 1927. Serial No. 219,243.

This invention relates to sound reproducing sets especially intended for use in the guest rooms of a hotel in connection with a circuit channel leading to such guest room 5 from a remote radio receiver or a microphone circuit whereby the guest may hear an entertainment program which is being distributed in like manner throughout the hotel.

One object of the invention is to avoid the 10 expense of building the operating parts of the set into the walls of the room while at the same time securing the same advantage of making such operating parts substantially theft proof and the additional advantages of 15 the connection of the set to a base board receptacle, thereby readily adapting it for installation in hotels not originally equipped for guest room radio service, of the ready portability of the set within such limits of 20 the guest room as will promote the guest's convenience in its use, and of a conveniently located selector switch by which the operation of the set may be controlled.

A further object of the invention is to combine, as to the operating parts of such a set, 25 the advantages of normal concealment when the set is not in use, instant accessibility when its use is desired, and concealment of all operating parts except the reproducing means 30 when its use is in progress.

With the foregoing objects in view I provide a table or somno, useful as a bedside stand, having a drawer serving as a receptacle for the operating parts which are included in 35 the combination in which the invention generally consists. Such operating parts comprise earphones, a control switch and a switch box, the control switch and switch box being permanently mounted in the drawer and the 40 earphones removable from the drawer for the purpose of use. The terminals of the base board plug and earphone circuits are connected to the control switch and enclosed in the switchbox so as to render them inacces- 45 sible, and the outward movement of the drawer is limited to an extent sufficient only to permit the easy removal of the earphones and operation of the switch handle. Thus while convenience in use is afforded the operating parts 50 are effectively secured against breakage, tam-

pering or removal. A further feature of this construction is that the drawer may be closed whether or not the set is in use, whereby when not in use all the operating parts are concealed, and when in use all parts except the 55 earphones are concealed, such arrangement permitting the orderly appearance of the guest room to be maintained at all times.

An embodiment of the invention is illus- 60 trated in the accompanying drawings where- in:

Figure 1 is a partly broken perspective view of the set with the drawer in open position, the broken part showing the general ar- 65 rangement of the parts.

Figure 2 is a central vertical sectional view. The somno comprises a table or stand 1 having a top 2 and shelf 3 upon which a telephone, magazines and other articles may be placed. For the accommodation of the operating parts, the somno includes a suitably mounted drawer 4, the outward movement of which is limited by any suitable means such as a block 5 which is secured to the upper side of the somno top 2 and abuts against the rear of the drawer when the drawer is opened. The operating parts of the set includes the earphones 6 with their circuit cord 7, switch box 8 carrying a control switch, and a projecting control switch handle 9 preferably extending from the top of the switch box. The incoming circuit channel terminates in a socket (not shown) to which the set is connected by a baseboard plug 10 and cord 11 which has its terminals connected within the switch box 85 and extends through openings 12 in the rear walls of the cabinet and drawer. The switch box is permanently mounted in the drawer 4 in a position such that ample space is provided for the storage in said drawer of the ear phones 6 and cord 7. The terminals of the cords 7 and 11 are of course connected within the switch box to elements of the switch in such a manner that the closing of the switch will connect the two circuits together. It is to be understood, however, that if more than one incoming circuit be provided, the circuit cord 11 will have a similar number of circuit wires leading to and connected with the control switch and that the control switch will be of 90 95 100

a type suitable to connect the phone cord with any of such circuits.

In order to permit the closure of the drawer and thus to conceal the switchbox 5 when the ear phones are in use, a clearance, indicated at 13, is formed between the front upper edge of the drawer and the overlying edge of the somno. This clearance may be formed in any manner as by cutting away a 10 portion of either or both edges.

The set may be operated by opening the drawer 4, removing the ear phones 6 and operating the control switch by appropriately moving the switch handle 9. The occupant, 15 if he so desires may then reclose the drawer, the cut away portion 13 providing a clearance for the phone cord 7.

Having fully described my invention, I claim:

20 1. A set for reproducing the sound modulated current of an incoming channel of communication including a stand having a normally closed compartment, a switch box permanently mounted in the compartment 25 and having a projecting switch handle, ear phones having a cord connection to the switch box and normally contained in but removable from the compartment and a cable connection to said channel extending externally 30 of the stand and having its terminals connected within the switch box, said compartment being movable outwardly with respect to said stand, and a stop arranged to permit outward movement of said compartment to 35 such an extent as to give access to the ear phones and the switch handle while preventing outward movement of the compartment to such an extent as to give access to the mounting of the switch box.

40 2. A set for reproducing the sound modulated current of an incoming channel of communication including a stand having a normally closed compartment, a switch box permanently mounted in the compartment 45 and having a projecting switch handle, ear phones having a cord connection to the switch box and normally contained in but removable from the compartment and a cable connection to said channel extending externally of 50 the stand and having its terminals connected within the switch box, said compartment being movable outwardly with respect to said stand, and a stop arranged to permit outward movement of said compartment to 55 such an extent as to give access to the ear phones and the switch handle while preventing outward movement of the compartment to such an extent as to give access to the mounting of the switch box, said compartment 60 having a cutaway portion to provide a clearance for the cord of the ear phones to permit the use of such phones while maintaining the compartment closed.

65 3. A set for reproducing the sound modulated current of an incoming channel of com-

munication including a stand having a normally closed drawer, a switch box permanently mounted in the drawer and having a projecting switch handle, ear phones having a cord connection to the switch box and normally contained in but removable from the drawer and a cable connection to said channel extending externally of the stand and having its terminals connected within the switch box, said drawer being movable outwardly with respect to said stand, and a stop arranged to permit outward movement of said drawer to such an extent as to give access to the ear phones and the switch handle while preventing outward movement of the drawer to such an extent as to give access to the mounting of the switch box.

4. A set for reproducing the sound modulated current of an incoming channel of communication including a stand having a normally closed drawer, a switch box permanently mounted in the drawer and having a projecting switch handle, ear phones having a cord connection to the switch box and normally contained in but removable from the drawer and a cable connection to said channel extending externally of the stand and having its terminals connected within the switch box, said drawer being movable outwardly with respect to said stand, and a stop arranged to permit outward movement of said drawer to such an extent as to give access to the ear phones and the switch handle while preventing outward movement of the drawer to such an extent as to give access to the mounting of the switch box, said drawer having a cutaway portion to provide a clearance for the cord of the ear phones to permit the use of such phones while maintaining the drawer closed.

In testimony whereof I hereby affix my signature.

KARR PARKER.
